Primary Examiner—Bernard Ansher*Assistant Examiner*—Adir Aronovich*Attorney, Agent, or Firm*—Samuel R. Williamson**[57] CLAIM**

The ornamental design of a camera module for a personal computer, as shown and described.

DESCRIPTION

FIG. 1 is a top, front and right side perspective view of a camera module for a personal computer showing our new design;

FIG. 2 is a front elevation thereof;

FIG. 3 is a rear elevation thereof;

FIG. 4 is a top plan view thereof;

FIG. 5 is a right side elevation, the left side elevation being a mirror image thereof; and,

FIG. 6 is a bottom plan view thereof.

*FIG. 1**FIG. 2**FIG. 3**FIG. 4*

FIG. 5

FIG. 6
